(57) **CLAIM**

The ornamental design for a transparent casket, as shown and described.

DESCRIPTION

FIG. 1 is a front, top perspective view of a transparent casket showing our new design;

FIG. 2 is a front elevational view thereof, the rear elevational view being identical thereto;

FIG. 3 is a right end elevational view thereof, the left end elevational view being identical thereto;

FIG. 4 is a top plan view thereof; and,

FIG. 5 is a bottom plan view thereof.

1 Claim, 3 Drawing Sheets

FIG. 1

FIG. 2

FIG. 3

FIG. 4

FIG. 5
